INSTRUMENT FOR DRAFTING

Filed May 19, 1927

UNITED STATES PATENT OFFICE.

JAMES A. NELL, OF NEW BRITAIN, CONNECTICUT.

INSTRUMENT FOR DRAFTING.

Application filed May 19, 1927. Serial No. 192,668.

This invention relates to instruments for drafting and of the type disclosed in Letters-Patent, No. 1,492,893, issued to me May 6th, 1924.

5 The objects of the present invention are to provide a simple instrument free of movable parts the use of which will facilitate the drawing of lines in parallel or any desired angular relation; to provide in such an instrument 10 protractor elements whereby a given angle may be quickly and accurately measured or lines drawn to define a desired angle; to provide means whereby certain fixed or standard angles may be easily 15 marked; to provide means whereby small circles may be accurately formed without the use of a compass, and to generally enlarge the range of usefulness of the device. These 20 stated objects and other objects which will 25 hereinafter incidentally appear are attained in such an instrument as is illustrated in the accompanying drawing, and the invention resides in certain novel features which will be particularly pointed out in the appended claim.

The drawing is a plan view of an instrument embodying the invention.

The device consists essentially of a rectangular frame having end members 1 and 2 30 and side members 3 and 4, each of said members having parallel edges. The frame may be constructed of an integral thin metal plate faced with celluloid or the like, or it may be made from strips secured together by any 35 convenient means, the total thickness being from .035 to .050 of an inch so that, while the instrument will be durable, weight and bulk will be avoided. At the outer corners of the 40 frame, narrow thin L-shaped strips 5 are secured upon its face so as to reinforce the frame and also prevent it from slipping under a T-square when used therewith.

Each of the members 1, 2, 3 and 4 is formed 45 with a longitudinal slot 6 extending parallel with the sides of the member and so located that the member is divided into an outer relatively narrow rail and an inner relatively wide rail. In the wider rail of each end member 1, 2, is a longitudinal slot 7 parallel 50 with the slot 6 but narrower and having one end located in alignment with the inner edge of the side member 4 and the opposite end disposed near an end of the slot 6 in the member 3 and curved slightly toward the same, as 55 shown at 8. In the wider rail of said member 3 are aligned longitudinal slots 9 which

have their inner ends near the center of the rail and their outer ends near the curved ends of the slots 7, a short web 10 separating the inner ends of the slots and similar webs 11 60 separating their outer ends from the slots 7. The ends of the slots 9 are also so arranged relatively to the curved ends of the slots 7 that they may be marked with graduations giving a continuous scale reading. Along 65 both edges of all the members 1, 2, 3 and 4 are scales, indicated at 12, graduated in inches and fractions of inches and like scales are inscribed along the sides and ends of the slots 6, as indicated at 13, while along the outer 70 sides of the slots 7 and 9 are scales 14 graduated in degrees of a circle and fractions thereof and along the inner sides of said slots are graduations 15 marking five degree intervals. Preferably, the notations of these scales 14 75 and 15 run in opposite directions, the zero point of the scale 15 being at the web 10 and the zero point of the scale 14 being on the line of the inner edge of the member 4 extended.

In the wider rail of the member 4 are 80 arcuate slots 16 arranged in a series with their ends overlapping so that they constitute a protractor with the degree scales 17 merging to furnish a continuous reading. At opposite sides of the protractor slots 16 are openings 85 18, 19, of a general triangular form and each having two straight sides 20 disposed at an angle of 120° to facilitate drawing two sides of a hexagon. At the base of the opening 18 is an arcuate projection 21 while from the base 90 of the opening 19 projects a point 22 the sides of which define an angle of 82° for use in drawing the under side of a flat head screw, and circular holes 23 are formed through the device at various points to provide for 95 drawing small circles without a compass. These holes have diameters, varying by 1/64 of an inch, from 3/64 of an inch to 13/32 of an inch and the identifying designations are placed on the face and also on the back of 100 the instrument and the identifying designations in decimal equivalents of an inch are placed on the back of the instrument to avoid excessive crowding on the face thereof, the designations of the angles 82 and 120 being 105 placed on the back for the same reason. The notations for the scales of linear measurement are carried from the center to both ends of the scale so that the measurement may be read in the most convenient way in any 110 given case.

The instrument will generally have an out-

- side measurement of 6 x 9 inches but it may be made in various sizes, although the proportions will always be the same. The outer rails are one-half inch wide and the inner rails are three-fourths of an inch wide while the slots 6 are one-fourth of an inch wide thus making it possible to draw parallel lines $\frac{1}{4}$, $\frac{1}{2}$, $\frac{3}{4}$, 1 or $1\frac{1}{2}$ inches apart with any member of the instrument with a single setting.
- 10 To compensate for the thickness of the pencil mark and attain accuracy in the measurements, the rails are about .015 of an inch short of their rating while the slots are a like amount in excess of their rating.
- 15 The instrument is used on a drawing board in connection with a T-square in the same manner that a triangle is used, and it will be obvious that any edge of any member of the instrument may be used for drawing a line.
- 20 Lines at right angles may be drawn with the corners of the instrument within its capacity and by shifting the instrument quadrangles may be quickly constructed. Angles other than right angles may be drawn. Let it be assumed that a line is to be drawn upwardly and inclined to the right with respect to the base line. The instrument is so placed that the inner edge of the member 4 is on the base line and the zero point of the inside rail is at the point where the lines are to intersect.
- 25 A pencil dot is placed at said point and another dot is placed at the proper degree notation, on the member 2 whereupon the instrument is moved until one edge alines with the two dots, the required line being then drawn in an obvious manner. Let it be assumed that an inclined line is to be drawn upwardly

to the left from a base line. The instrument is placed as just described and then moved toward the position of the line to be drawn, 40 the base line being observed through the slot 7 in the member 2 and the zero point of the member 4 being kept at the point of intersection with the base line. When the base line registers with the proper degree notation the 45 instrument will be in position to locate the line to be drawn, and the base line should register with the same notation in the minor protractor there thus being three points of alinement. The desired line may then be 50 drawn.

It is to be understood that the accompanying drawings are illustrative only and not restrictive and that the details of the instrument may be varied without departing from 55 the spirit or scope of the invention as the same is defined in the following claim.

Having fully described my invention what I claim as new and desire to secure by Letters-Patent, is:—

A drafting instrument comprising four members joined to form a rectangular frame, three members of which are provided with longitudinal slots and have degree graduations along the edges of said slots forming 65 a major protractor, and the fourth member having an arcuate slot with degree graduations along the edge of the same forming a minor protractor, all said graduations radiating from a common center on the fourth member of the frame. 70

In testimony whereof, I have signed this specification.

JAMES A. NELL.
